UNITED STATES PATENT OFFICE.

FLORENCE STOCKDALE, OF CHICAGO, ILLINOIS.

SKIRT-MARKER.

1,254,945.

Specification of Letters Patent. Patented Jan. 29, 1918.

Application filed March 15, 1917. Serial No. 155,033.

To all whom it may concern:

Be it known that I, FLORENCE STOCKDALE, a citizen of the United States, residing at Chicago, in the county of Cook and State 5 of Illinois, have invented certain new and useful Improvements in Skirt-Markers; and I do declare the following to be a full, clear, and exact description of the invention, such as will enable others skilled in the art to 10 which it appertains to make and use the same.

My invention relates to dressmaking and more particularly to that class of apparatus used for skirt gages or markers.

15 One object of the invention is the provision of a skirt marker which may be readily adjusted and is easily operated, while at the same time giving the greatest accuracy.

20 A further object is to provide a marker in which means are provided to hold the portion of a skirt adjacent the edge of the marker so that it will not slide thereon, and at the same time provide a device which will 25 permit of the movement of the marker on the inner side of the skirt without catching in or wrinkling the skirt in any way.

To this end, my invention consists of the 30 novel features of construction, combination and arrangement of parts to be hereinafter described and claimed, the descriptive matter being supplemented by the accompanying drawing in which:

Figure 1 is a sectional view showing my 35 invention in use;

Fig. 2 is a perspective view; and

Fig. 3 is a detail vertical transverse section on the line 3—3 of Fig. 2.

Referring to the drawings 1 designates 40 the base of the marker which in my preferred form is of substantially triangular shape and is provided at one end with a handle 2. At the opposite end the usual square upright 3 is provided which carries 45 scale markings on its front and rear faces.

A flat marking plate 4 having a straight rear edge 5 and an arcuately curved front edge 6 is adapted for engagement with the post 3. This marking plate is provided with 50 a slot 13 adjacent its rear edge and which communicates therewith, and is shaped to conform with the outline of the post 3 which is received in the slot to permit sliding movement of the marking plate with respect 55 to the post. Secured at one end to the rear

edge 5 of the marking plate is a spring bar 7 which extends across the outer end of the slot 13 and has its free end terminating flush with the end of the plate 4. Adjacent the slot 13 this bar is provided on its inner surface with a cushioning element 8 which may be composed of any suitable material, but in this form comprises a piece of felt glued or otherwise attached to the face of the bar. 60

Extending longitudinally through one end 65 of the marking plate is a bolt 10 having its head disposed in a recess 11 formed in the front edge of the marking plate. The end of the bar 7 adjacent the bolt is provided with an enlarged bore 9 to receive the projecting stem of the bolt therein and permit movement of the bar with respect to the stem of the bolt. Threaded on the outer end of the bolt is an ordinary thumb nut 12 which when tightened contacts with the 70 adjacent face of the bar 7 and forces the same inwardly against the rear edge of the plate 4.

By this operation, the cushioning member 8 will be brought into contact with the 80 adjacent face of the post 3 to frictionally bind the plate 4 to the post at the point desired.

In the present instance the bar 7 is constructed of resilient metal but it may readily be perceived that any suitable material may be used to accomplish the same result. Also any suitable fastening means may be secured to the bar against the rear edge of the plate without departing from the spirit 85 of my invention.

The front edge 6 of the marking plate is beveled inwardly from its top to its bottom to provide a thin edge upon which is placed a strip of felt 14 having its edges secured 90 on the top face of the plate and in the bevel on the under side of the plate. This strip of material 14 is provided to prevent shifting of the portion of the skirt in contact with the edge 6 as it will frictionally hold 95 the skirt thereon. Owing to the arcuate construction of the front edge of the plate the marker may be moved around against the skirt without catching in or in any way rumpling up or disturbing the adjustment 100 of the skirt.

In the operation of my device the marking plate is adjusted to the desired height on the post by means of the tightening of the bolt 12 which serves to frictionally bind 110

the plate to the post, after which the front edge of the plate is brought in contact with the inner surface of the skirt, and a piece of tailor's chalk moved over the outside of the skirt along the arcuately curved edge which will serve to outline on the skirt the point at which it is desired to be turned or hemmed, or in any other manner adjusted. By grasping the handle 2 the base may be moved 10 inside of the skirt correspondingly carrying the marker without in any way changing the adjustment, and it is to be understood that I do not limit myself to the specific details and materials described herein as any 15 substitutes may be employed, and minor changes in the details of construction may be made without in any way departing from the scope of the invention.

Copies of this patent may be obtained for five cents each, by addressing the "Commissioner of Patents, Washington, D. C."

I claim:

A skirt marker comprising the combination 20 with a base having an upright extending therefrom; of a marking plate having front and rear edges and provided with a slot in its rear edge for receiving said upright therein, a spring arm on said plate, 25 and means for forcing said arm against the upright, whereby to adjustably bind the marking plate at any desired point on the upright.

In testimony whereof I have hereunto set 30 my hand in the presence of two subscribing witnesses.

FLORENCE STOCKDALE.
